UNITED STATES PATENT OFFICE.

SAMUEL L. COALES, OF NEWPORT-PAGNELL, ENGLAND.

DOOR-LATCH.

SPECIFICATION forming part of Letters Patent No. 280,581, dated July 3, 1883.

Application filed January 22, 1883. (Model.) Patented in England June 24, 1881, No. 2,759.

To all whom it may concern:

Be it known that I, SAMUEL LILLEY COALES, of Newport-Pagnell, England, have invented new and useful Improvements in Door-Latches, 5 (for which I have obtained a patent in Great Britain, No. 2,759, bearing date June 24, 1881,) of which the following is a specification, reference being had to the accompanying drawings.

The object of my invention is to provide an 10 improved door-latch which is so constructed that the bolt thereof may in a very simple manner be drawn back to release the door by lifting, pulling, or pushing a handle or handles, instead of turning the same to the right or left 15 in the ordinary manner.

My improved latch may or may not be furnished with mechanism to permit the locking of the bolt by means of a key.

The said invention is illustrated in the accompanying drawings, in which Figure 1 is a side view, Fig. 2 a front view, and Fig. 3 a plan or top view, of my improved door-latch. Fig. 4 is a side view of the same with the cover, and also the sliding piece hereinafter 25 described, removed therefrom. Fig. 5 represents a top view of the sliding piece shown in Figs. 1 and 3, and Fig. 6 is a similar view of a slightly-modified form of the same. Fig. 7 is a front view of my improved latch inserted 30 within a door, and represents the same provided with two handles—one on each side of the said door—for operating the bolt.

Like letters indicate the same parts throughout the drawings.

35 *a* represents the case or box of my improved latch, and *b* is the bolt arranged to slide or travel within the said case or box *a*. One end of this bolt *b* has the usual inclined surface, *b'*, which, when projected forward, extends out- 40 side of the aforesaid case and into the door frame, post, or lintel, in the usual manner, to keep the door closed. The inner portion of the said bolt is provided with an aperture or slot, *b''*, which extends completely through the 45 metal of which the said bolt is formed. At the rear end of the latter, and preferably formed in one piece therewith, is a rod or extension, *c*, which fits into an aperture at *a'* in the rear wall of the box or case *a*, and, when 50 the said bolt is withdrawn, slides rearward through the said aperture into a space which is formed or provided in the wood of the door be-

fore securing the latch in position. Upon this rod or spindle is placed a coiled spring, *d*, one end of which abuts against the inner surface 55 of the rear wall of the box *a* and the other end against the rear end of the bolt, as shown, the said spring being so arranged that it constantly tends to shoot or force the said bolt forward. This spring is compressed when the bolt is 60 drawn back, as hereinafter explained. Any other suitable spring may be employed in place of that shown. Within the aforesaid aperture *b''* in the bolt *b*, and at the rear end thereof, I provide an anti-friction roller, *e*, against which 65 works the sliding piece *f*, constructed as follows—that is to say, this sliding piece is formed on one side with two precisely similar inclined surfaces, *f'* *f''*, which are slightly curved and extend in opposite directions from 70 the central part, *f''*, of the said piece *f*. These surfaces terminate in shoulders that serve as stops to limit or arrest the transverse movement of the said sliding piece when the same has been moved in either direction a sufficient 75 distance to complete the drawing back of the bolt. The opposite side of the said sliding piece is straight and slides against the forward edge of the rectangular slots *g* in the walls 80 of the box or case *a*. One of the inclined surfaces *f'* slides over the friction-roller *e* when the sliding piece *f* is pushed or pulled in one direction, and the other surface when the said piece is pushed or pulled in the other direction, the bolt being thus withdrawn and, with 85 the spindle *c*, forced rearward, so as to compress the spiral spring *d*. As soon, however, as the sliding piece *f* is released, the said spring comes into action and pushes or projects the bolt *b* forward into its normal position. In 90 some cases the rod or spindle *c* may be arranged to work entirely within the case or box, instead of in a recess in the door beyond the said case.

In order to impart the desired transverse 95 movement to the aforesaid sliding piece *f*, I provide the same with apertures *h*, into each of which projects one end of one of the levers or projections *i*, forming part of or connected with the handles *j*. The outer surface, *h'*, of these 100 apertures may be straight, but is preferably rounded, as will be understood by reference to Fig. 6. One of the said handles is preferably arranged on each side of the door, as shown

in Fig. 7, and the levers *i* are pivoted at *i'* to suitable plates, *k*, attached to the said door, so that when one of the said handles is lifted, as shown in this figure, it will pull the sliding piece *f* outward, and thus withdraw the bolt and allow the door to be opened. The said handles may be made of any desired shape and ornamented or decorated in any style. The handle may, moreover, if desired, serve also as a door-knocker, or be connected with a gong or bell. When it is desired that the door should be unlatched from one side only, one handle only need be employed.

When it is desired to provide means for locking the bolt *b*, I prefer to arrange mechanism within the box or case *a* for this purpose, as follows—that is to say, I provide a small sliding plate, *l*, which works in a direction at right angles to the path of movement of the bolt *b*. The part *l'* of this sliding plate, when raised, serves, in combination with the shoulder *b**, as a stop to prevent the inward movement of the bolt *b*. The said sliding plate is provided with a suitable notch, 25 with which the key engages, and with preferably two tumblers or detaining pieces, *m*, which fit over a projection, *l'*, on the said piece *l*. The said tumblers are connected with separate springs at *n*, which retain them in 30 their proper position to prevent the movement of the sliding plate excepting when the key is used. This key is so formed that it pushes back the said tumblers, and thus disengages the projection *l'* and allows the plate to be 35 moved on the turning of the key.

The latch above described is very simple in its construction and operation, and is very durable. Moreover, if the key should be left in the door, no injury to the knuckles can accrue in the opening of the said door, and the latch 40 can be drawn back very easily. Furthermore, the bolt may be readily reversed, so as to suit a right or left hand door, and the sliding piece *f* for one thickness of door may be easily replaced by another piece of different length to 45 suit a door of greater or less thickness.

My said invention is particularly applicable to mortise-latches, but may, with obvious modifications, be applied to other kinds of latches, and the bolt may be arranged to be withdrawn 50 either by lifting, pulling, or pushing the handle, in connection with the sliding piece *f*, which operates the bolt.

What I claim is—

In a door-latch having a spring-bolt operated 55 by a sliding plate having inclined surfaces which act upon a friction-roller journaled in said bolt, a pivoted elbow-lever, one arm of which engages in an aperture in the plate to force it outward, and the other arm carrying a gravity-knob which is adapted to be used 60 as a knocker by oscillating the lever upon its pivot *i'* and striking the door with said knob, as and for the purposes set forth.

SAMUEL LILLEY COALES.
